H. W. HOWES,

COMMUTATOR.

APPLICATION FILED SEPT. 22, 1920.

1,415,931.

Patented May 16, 1922.

Inventor:
Horace W. Howes.
By his attorney,
Charles S. Gooding.

UNITED STATES PATENT OFFICE.

HORACE W. HOWES, OF WALTHAM, MASSACHUSETTS.

COMMUTATOR.

1,415,931.

Specification of Letters Patent. Patented May 16, 1922.

Application filed September 22, 1920. Serial No. 411,943.

To all whom it may concern:

Be it known that I, HORACE W. HOWES, a citizen of the United States, residing at Waltham, in the county of Middlesex and 5 State of Massachusetts, have invented new and useful Improvements in Commutators, of which the following is a specification.

This invention relates to a commutator for internal combustion engines.

10 The object of the invention is to provide a simple, easily operated and easily adjusted mechanism which can be used in connection with a combustion engine of the well-known Ford type and which, when so used, locates 15 the rotary and stationary contact members of the commutator in a convenient and easily accessible position and also locates them in a position where they are removed from the oil and dirt ordinarily to be found at the end 20 of the cam shaft.

The object of the invention is further to provide a device of the character hereinbefore set forth in which the rotary member of the commutator is operated from the cam 25 shaft of the engine and the stationary contact members may be adjusted simultaneously by means of a rod connected to the usual spark control lever.

The object of the invention is further to 30 provide a device of the character set forth in which there is a convenient means for taking up backlash in the gears which operate the rotary contact member of the commutator.

35 The invention consists in the combination and arrangement of parts set forth in the following specification and particularly pointed out in the claims thereof.

Referring to the drawings:

40 Figure 1 is a front elevation of my improved commutator showing the same attached to the cam shaft gear casing cap of a Ford automobile.

Fig. 2 is a sectional elevation taken on the 45 line 2-2, Figure 1.

Fig. 3 is a detail plan view of the rotary and stationary contact members with the cap of the stationary contact member casing removed.

50 Like numerals refer to like parts throughout the several views of the drawings.

In the drawings, 5 is a stationary support constituting a portion of a Ford engine and being adapted to be fastened by screws 6 to 55 the cylinder block of a Ford engine and constituting a cover for the timing gears.

7 is a frame consisting of a hollow body portion 8 with oppositely disposed arms 9 and 10 thereon and with upwardly extending arms 11 and 12 which converge toward each other to support a bearing 13. Another bearing 14 is provided in said body portion and in the two bearings 13 and 14 a sleeve 15 is rotatably mounted, said sleeve having fastened thereto a bushing 16. The sleeve 15 has an arm 17 fast thereto upon which is swivelled a block 18, said block being connected by a rod 19, and other connections, to the spark lever at the top of the steering post in a manner well known to those skilled in this art, but not shown in the drawings. A casing 20 preferably composed of insulating material and provided with a chamber 21 has a hub 22 concentric therewith which is fastened by means of a set screw 75 to the sleeve 15 so that said chamber can be rocked by the spark lever and by means of the rod 19 and said connections. A plurality of stationary contacts 23 are provided in the casing 20 and are fastened to said casing at the bottom of the chamber 21 and concentric with the sleeve 15. These contacts are connected by wires 24 to contact posts 25. In the present case there are four of these contact posts, one for each cylinder of 80 the internal combustion engine and said contact posts are connected by wires in a well-known manner to the coil units of a magneto.

A vertically arranged shaft 26 is rotatably mounted in the sleeve 15 and to its upper end is attached a rotary contact member consisting of an arm 27 in which is slidably mounted a contact member 28 which is held by a spring 29 in contact with the bottom surface of the chamber 21 in the casing 20, said contact member 28 being concentric with the shaft 26 and adapted to successively engage the stationary contacts 23 when the shaft 26 and the arm 27 are rotated. The 95 shaft 26 is rotated by means of a bevel gear 30 fast to the lower end thereof and meshing into a bevel gear 31 which is fastened to the cam shaft 32 of said internal combustion engine. The frame 7 is pivoted on a stud 33 fast to the stationary support 5 and the arm 9 is provided with a slot 34 through which projects a clamping screw 35 having screw-threaded engagement with the stationary 100 support 5 so that the frame 7 can be raised and lowered slightly by tipping the same

upon its pivot 33 and clamped in adjusted position by means of the clamping member 35. Thus the gear 30 can be adjusted slightly with relation to the gear 31 and backlash or wear may be thus taken up.

The general operation of the device is as follows:—Assuming the parts to be in the relative positions illustrated in the figures of the drawings, the rotary contact member 27 will be rotated around in the chamber 21 by means of the shaft 26 and the bevel gears 30 and 31 and shaft 32, and will successively contact with the stationary contact members 23, thus making and breaking the primary circuit and determining the instant at which the spark plugs of the engine must fire. When the rotary contact member in revolving engages the four stationary contact points 23, in succession, to each of which is attached a wire connected with a coil unit, an electric circuit is passed through the system of primary wires in a manner well known to those skilled in the art. If it is desired to advance the spark, the sleeve 15 together with the casing 20 and the stationary contact points 23 fast thereto are rotated in one direction by means of the spark lever connected to the sleeve, as hereinbefore set forth by the rod 19 and other connections. If it is desired to retard the spark, the spark lever is moved in the opposite direction and the casing 20 with the stationary contacts is also moved in the opposite direction, thus retarding the spark.

35 I claim:

1. A commutator for internal combustion engines having, in combination, a frame, a sleeve rotatably mounted therein and supported at its opposite ends by bearings in said frame, a shaft rotatably mounted in said sleeve, a rotary contact member fast to said shaft, a plurality of stationary contact members adapted to be engaged by said rotary contact member, spaced apart, mounted upon said sleeve and insulated therefrom, means to rotate said shaft, and means to simultaneously adjust said stationary contact members concentrically with said shaft.

2. An internal combustion engine having, 50 in combination, a stationary support, a rocker frame mounted upon said stationary support, means to lock said rocker frame in different positions relatively to said stationary support, a sleeve rotatably mounted on said rocker frame and supported at its opposite ends by bearings in said frame, a shaft rotatably mounted in said sleeve, a contact member fast to one end of said shaft, a gear fast to the other end of said shaft, a 55 plurality of stationary contact members spaced apart, mounted upon said sleeve, concentric therewith and insulated therefrom, said stationary contact members being adapted to be engaged successively by said 60 rotary contact member, a cam shaft, a gear 65

fast to said cam shaft and meshing in said first-mentioned gear and means to rock said sleeve, whereby said stationary contact members may be simultaneously adjusted relatively to said rotary contact member.

3. A commutator for internal combustion engines having, in combination, a frame, a sleeve rotatably mounted therein and supported at its opposite ends by bearings in said frame, a shaft rotatably mounted in said sleeve, a rotary contact member fast to said shaft, a casing provided with a chamber and fast to said sleeve in which said rotary contact member is located, a plurality of stationary contact members located in said chamber adapted to be engaged by said rotary contact member, spaced apart and insulated from said rotary contact member, means to rotate said shaft, and means to adjust said sleeve whereby said stationary contact members may be simultaneously adjusted relatively to said rotary contact member.

4. A commutator for internal combustion engines having, in combination, a frame, a sleeve rotatably mounted therein and supported at its opposite ends by bearings in said frame, a shaft rotatably mounted in said sleeve, a rotary contact member fast to said shaft, a casing of insulating material provided with a chamber and fast to said sleeve, a plurality of stationary contact members located within said chamber fast to said casing and concentrically arranged with relation to said rotary contact member, said stationary contact members being spaced apart, means to rotate said shaft, and means to rotate said sleeve whereby said casing and said stationary contact members may be simultaneously adjusted relatively to said rotary contact member.

5. An internal combustion engine having, in combination, a stationary support, a rocker frame, a pivot fast to said stationary support upon which said rocker frame is mounted, a clamping member fast to said stationary support and adapted to clamp said frame to said stationary support, a sleeve rotatably mounted on said rocker frame, a shaft rotatably mounted in said sleeve, a contact member fast to one end of said shaft, a gear fast to the other end of said shaft, a casing fast to said sleeve provided with a chamber in which said rotary contact member is located, a plurality of stationary contact members spaced apart located within said chamber concentrically with said sleeve and insulated from said rotary contact member, said stationary contact members being adapted to be engaged successively by said rotary contact member, 115 a cam shaft, a gear fast to said cam shaft and meshing in said first-named gear, and means to rock said sleeve whereby said stationary contact members may be simultaneously adjusted relatively to said rotary contact member, 120 a cam shaft, a gear fast to said cam shaft and meshing in said first-named gear, and means to rock said sleeve whereby said stationary contact members may be simultaneously adjusted relatively to said rotary contact member, 125 a cam shaft, a gear fast to said cam shaft and meshing in said first-named gear, and means to rock said sleeve whereby said stationary contact members may be simultaneously adjusted relatively to said rotary contact member, 130

tact member and whereby one of said gears may be adjusted relatively to the other.

6. A commutator for internal combustion engines having, in combination, a stationary support, a pivot thereon, a frame mounted on said pivot, means to clamp said frame to said stationary support, a vertical shaft rotatably mounted on said frame, a contact fast to the upper end thereof, a gear fast to the lower end thereof, a horizontal shaft rotatably mounted in said stationary support and a gear fast to said horizontal shaft and meshing into said first-named gear, whereby one of said gears may be adjusted relatively to the other.

7. A commutator for internal combustion engines having, in combination, a frame, a pair of bearings on said frame spaced apart, arms connecting said bearings together, a sleeve rotatably mounted at its opposite ends

in said bearings, a shaft rotatably mounted in said sleeve, a rotary contact member fast to said shaft, a plurality of stationary contact members adapted to be engaged by said rotary contact member spaced apart, mounted upon said sleeve and insulated therefrom, means to rotate said shaft and an arm fast to said sleeve and projecting outwardly therefrom between said arms whereby said stationary contact members may be simultaneously adjusted concentrically with said shaft.

In testimony whereof I have hereunto set my hand in presence of two subscribing witnesses.

HORACE W. HOWES.
